Alonzo Hebbard, of New York, N.Y.

Assignor to
W. Gale Jr. and J. R. Willis, of same place.
Letters Patent No 1329, dated Oct. 2. 1860.

The schedule referred to in these Letters Patent and making part of the same.

To all whom it may concern:

Be it known that I, Alonzo Hebbard, of the City, County and State of New York, have invented or produced a new and original Design for Table and Tea Spoons, and I do hereby declare that the following is a full, clear and exact description of the same, reference being had to the annexed drawings making a part of this Specification, in which

Figure 1. is a face view, and

Figure 2. a back view of a table spoon constructed according to my design.

The contour or outline of the spoon is the same or similar to that in general use. A represents the bowl and B, the handle. The front surface or exterior of the bowl A, is perfectly plain or has no ornamentation as will be seen by referring to figure 1.

The front surface of the handle B, however at its outer part has a

series of egg-shaped projections a. encompassed each by an oval ledge b. which are in contact with each other and form a chain-like ornamentation which conforms to the contour of the outer part of the handle and are enclosed by beads c. c. the outer ends of which are curved in scroll form and have a set ornament d. between them which forms the extreme end of the handle.

At the inner ends of the beads c. c. there are leaf like scrolls e. which branch out from either side of a series of circular knobs or projections f. which gradually decrease in diameter as they extend inward towards the bowl A. The face side of the handle B. is also provided with beads g. g. which follow its outline, are curved at their inner ends, and terminate with a set ornament h. a series of circular knobs or projections i. of gradually diminishing diameter being between the inner parts of the beads g. g.

The above parts comprise the whole of the ornamentation on the front or face side of the spoon as shown in figure 1.

The back surface of the handle B. of the spoon as shown in figure 2, has its outer part provided with egg-shaped projections a. encompassed by oval ledges b. It also has the set ornament d. the leaf like scrolls e. and knobs or projections f. are also used as well as the beads g. g. the latter however have a set ornament j. between their lower ends.

On the back convex surface of the bowl A. and adjoining the inner ends of the beads g. g. there is a set ornament formed of scrolls k. k. or pointed projections l. having upon it a series of circular knobs m. gradually decreasing in diameter and a leaf n. which forms a ground for the projection l.

The above described parts both on the face and back sides of the spoon are in relief.

What I claim as new and desire to secure by Letters Patent, is -

The general configuration as herein shown and described, to form a new and original design for a Table and Tea-Spoon.
